[57] CLAIM

The ornamental design for a fairing seal for aircraft canopy, as shown and described.

DESCRIPTION

FIG. 1 is a front left perspective view of a fairing seal for aircraft canopy showing my new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a rear elevational view thereof; and,

FIG. 7 is a bottom plan view thereof.

The fairing seal is shown broken away to indicate an article of indeterminate length.

FIG. 1

FIG. 2

FIG. 3

FIG. 4

FIG. 5

FIG. 6

FIG. 7
